LIVESTOCK PROD

William H. Abildgaard, Santa Maria, Calif., assignor to
Livestock Sprayer Mfg. Co., San Jose, Calif., a corpo-
ration of California

Application February 24, 1954, Serial No. 29,186

Term of patent 14 years

(Cl. D12—2)

FIG. 1

FIG. 2

FIG. 3

FIG. 4

To all whom it may concern:

Be it known that I, William H. Abildgaard, a citizen of the United States, residing in the city of Santa Maria, county of Santa Barbara, State of California, have invented a new, original, and ornamental Design for a Livestock Prod, of which the following is a specification, reference being had to the accompanying drawing, forming a part thereof.

Referring to the drawing:

Figure 1 is a plan view of a livestock prod, showing my new design.

Figure 2 is a side elevational view of the prod.

Figure 3 is a front elevational view of the prod.
Figure 4 is a rear elevational view of the prod.

I claim:
The ornamental design for a livestock prod, as shown.
